UNITED STATES PATENT OFFICE.

WARD E. PEARSON AND HENRY G. O'NEILL, OF NEW YORK, N. Y.

DESIGN FOR A PORTABLE ELECTRIC LAMP.

51,972.

Specification for Design.

Patented Apr. 16, 1918.

Application filed December 23, 1916. Serial No. 138,677. Term of patent 14 years.

To all whom it may concern:

Be it known that we, WARD E. PEARSON and HENRY G. O'NEILL, citizens of the United States, residing at New York city, in the county and State of New York, have invented a new, original, and ornamental Design for Portable Electric Lamps, of which the following is a specification, reference being had to the accompanying drawings, forming part thereof.

Figure 1 is a plan view, and Fig. 2 an edge view of a portable electric lamp, showing our new design.

We claim:

The ornamental design for a portable electric lamp, as shown.

WARD E. PEARSON.
HENRY G. O'NEILL.
